UNITED STATES PATENT OFFICE.

PHILIP N. SEA, OF CHICAGO, ILLINOIS.

PHONOGRAPH-RECORD ALBUM.

1,424,778.

Specification of Letters Patent. Patented Aug. 8, 1922.

Application filed May 5, 1920. Serial No. 379,189.

To all whom it may concern:

Be it known that I, PHILIP N. SEA, a citizen of the United States, and a resident of Chicago, in the county of Cook, State of Illinois, have invented certain new and useful Improvements in Phonograph-Record Albums, of which the following is a specification.

My invention relates to phonograph record albums and contemplates several improved features of construction and arrangement.

In the construction of my improved album leaf members in the form of envelopes extend from a back section which is hinged to a base, the leaf members underlapping at their outer ends to leave exposed sections for receiving printing indicative of the title of the record in the respective envelopes. A cover is provided for the album whose outer edge is behind the outer edge of the top envelope, so that the record indicating printing on the envelope is always visible.

In my construction the envelope opens at the side, and when an album is withdrawn from the phonograph cabinet it is of course easy to see whether a certain record is in its envelope. However, it is not always desirable to have to withdraw an album from the cabinet to ascertain whether or not a certain record is in place, and one of the important objects of my invention is therefore to provide simple indicating means which will indicate whether or not records are in the envelopes, without need of removing the album from the cabinet. This indicating means is preferably in the form of a sight opening in the top sheet of each envelope near the exposed edge thereof, and a colored or other conspicuous surface on the under sheet below the sight opening. When a record is in its envelope it will be below the sight opening and over the surface, but when the record is withdrawn the surface will show through the sight opening. The records being usually black, the color black will show through the sight opening when the record is in place and when the record is removed the white, colored or other conspicuous surface will be visible so that plain indication is given at all times whether or not a record is in place. Unless the color black shows at a sight opening the record is either in use or has been misplaced.

As records, particularly when of different types as, for example, Victor records and Columbia records, are of varying thickness and diameter I preferably make provisions for causing the records to be held forwardly sufficiently so that at their front edges they will fully underlie the respective sight openings so as to avoid false indication. This I preferably accomplish by means of elastic rivets or other fasteners yieldingly securing together the top and bottom sheets of an envelope adjacent the inner edge of the record, such elastic fastening members engaging with the inner edge of the record and urging it forwardly to keep its front edge underneath the sight opening. Any difference in thickness or diameter will thus be compensated for and the sight openings will always be covered whenever records are in the envelopes.

In my improved construction and arrangement the albums can be inserted in the phonograph cabinet with their printed ends exposed and one can see at a glance whether or not the record desired to be played is in its envelope without having to withdraw the album from the cabinet and open it up to the envelope indexed to contain such record. On the accompanying drawings the improved features of construction and arrangement referred to are clearly illustrated.

On the drawings:

Fig. 1, is a plan view of an envelope with part of the cover broken away,

Fig. 2, is a side elevational view,

Fig. 3, is an enlarged plan view of a section of the album, and

Fig. 4, is a sectional view on plane 4-4, Fig. 3.

The album shown comprises a base member 5, preferably of stiff material, and a cover member 6 also preferably of stiff material, the base and cover members at their rear edges being connected by a back member 7 which is also preferably of stiff material. The hinge connections 8 and 9 of the back member with the base and cover members respectively permit free relative swing of the members.

Secured to the back member 7 at regular intervals and extending forwardly therefrom between the base and cover members are the leaf members 10, these members being all of the same length, they being shown as

all having the same length as the base members 5. Each leaf member has upper and lower walls 11 and 12 which walls are disconnected except at their inner ends in order 5 to form record receiving envelopes or pockets 13. At their inner end the walls of each envelope are secured together as by gluing and are secured to the back number 7 by gluing their deflected rear edges or tongues 10 14 to the back member as clearly shown in Fig. 2. In the construction shown the envelopes are closed at their front ends and at one side, the opposite side being open for receiving records R, the top wall of each 15 envelope being cut away as indicated in Fig. 1 at 15 in order to expose a section of the enclosed record to permit the record to be more readily grasped for withdrawal.

The spacing of the leaf members along 20 the back section 7 is greater than the combined thickness of an envelope and a contained record in order that when the envelopes are all filled the back section 7 will be inclined rearwardly to cause the envelopes 25 to underlap at their front edges thereby to expose sections 16 on which may be printed the titles of the records contained within the respective envelopes. The cover member 6 is preferably also of the same 30 length as the leaf members so it will permit the top leaf member to project forwardly a distance to receive the record indication printing all as clearly shown in Fig. 1. With this arrangement the contents of the 35 various albums in a cabinet are visible without requiring withdrawal thereof or swinging back of the covers 6.

Describing now my improved means for indicating whether or not a record is in an 40 envelope, I provide a sight hole 17 in the top wall of each envelope adjacent its front edge and midway between its sides. On the bottom wall of each envelope below the sight hole I apply coloring material or a piece of 45 white or colored paper, or, if the color of the envelope paper is sufficiently conspicuous I use the natural surface on the bottom wall below the sight hole. With this arrangement when a record is placed in an 50 envelope it will underlie the sight hole and the black color of the record will show through the hole. On the other hand if the record is not in its envelope the back wall of the envelope will be visible through 55 the sight hole. If the natural color of the envelope material is such as to afford sufficient contrast between it and the black color of the record no coloring or colored material need be applied on the back walls. For example, if the envelopes are of white paper, 60 no coloring is necessary as the contrast between black and white is so great. However if the envelope material is of darker color so as not to afford sufficient contrast 65 then the wall below the sight hole may be

painted white or red or some other conspicuous color, or a sticker 18 of white or colored paper may be applied against the back walls below the sight openings. Referring to Fig. 1, records are in all the envelopes with the exception of the second and sixth. The color black therefore appears at each of the sight holes with the exception of the sight holes at the second and sixth envelopes where a much lighter 75 color appears, such lighter color clearly indicating that records are not in these envelopes. These sight holes are visible at all times even when the albums are lying on the shelves within the phonograph cabinet. A light colored sight hole indicates that the record belonging in the corresponding envelope is in use or has been misplaced in some other envelope, or a light colored hole will indicate an empty envelope available for a new record. 80

As records may vary slightly in thickness and diameter as for example Victor and Columbia records, I provide means for insuring proper positioning of the records in 90 the envelopes so that they will show below the sight hole. Referring to Figs. 1, 3 and 4 the means shown is in the form of elastic staples or stitches 19 extending through the top and bottom walls of each envelope adjacent the rear edge of the record. These elastic staples or stitches will exert forward pressure against the records to hold them with their front edges well against the front edges of the envelopes so that the sight openings will be fully covered. As shown holes 20 may be cut through the opposed walls of the envelopes and a rubber cord may be looped through the holes and tied preferably at the under side of the envelopes. Such 105 elastic members can be readily renewed should they break or wear out. Of course where the records in an album are all of the same thickness and diameter such elastic riveting means are unnecessary and inelastic 110 metallic or other rivet devices can be used for forming the rear abutments for records to hold them sufficiently forward in the envelopes when placed therein. 115

I thus produce a very efficient and useful phonograph record album whose indices and whose sight holes are always visible. Owing to the spacing of the leaf members being greater than the thickness of an envelope with a record therein the records can always 120 lie entirely flat and they will not be subjected to strain or warping. I do not desire to be limited to the precise construction and arrangement shown and described as modifications are possible which would still come 125 within the scope of the invention.

I claim as follows:

1. In a phonograph record album, the combination of a base, a cover, a back section hinged to the base and cover, a plurality 130

of envelopes hinged at their rear edges to said back, said envelopes being closed at their front edges and open at their side edges for the reception of records, said base 5 and envelopes and cover being all of the same length and spacing of said envelopes on said back being greater than the combined thickness of an envelope and the record therein whereby said envelopes when filled 10 will underlap each other at their front edges, there being a sight hole in the upper wall of each envelope at the center of its overlying section, the rear wall of each envelope being visible through said sight hole when a record 15 is not in the envelope and the record being visible through said sight hole when in the envelope.

2. In a phonograph record album, the combination of a folder structure, a plurality 20 of record-receiving envelopes bound in said folder structure, there being a sight hole in the top wall of each envelope near the front edge thereof, and an elastic abutment at the inner end of each envelope for engaging 25 with a received record and forcing it for-

wardly to hold its front end below said sight hole.

3. In a phonograph record album, the combination of a cover structure, a plurality of envelopes hinged at their inner ends to 30 said cover structure, each envelope having a sight hole in its upper wall adjacent its front edge, and elastic loops connecting the envelope walls at their inner ends, said elastic rivets adapted to engage with the rear edge 35 of a received record and force said record forwardly to hold its front end below said sight hole.

4. In a phonograph record album, the combination of a holder structure, a plurality 40 of envelopes hinged at their inner edges on said holder structure, each envelope having a sight hole in its upper wall adjacent the front edge, and means at the inner end of each envelope for forcing received records 45 forwardly into position with their front ends below the sight holes.

In witness whereof, I hereunto subscribe my name this 3rd day of May, A. D. 1920.

PHILIP N. SEA.
